UNITED STATES PATENT OFFICE.

WILLIAM WHARTON, JR., AND EDWARD SAMUEL, OF PHILADELPHIA,
PENNSYLVANIA, ASSIGNEES TO WILLIAM WHARTON, JR., AND COMPANY,
INCORPORATED, OF SAME PLACE.

DESIGN FOR A RAILWAY-RAIL.

SPECIFICATION forming part of Design No. 18,324, dated May 15, 1888.

Application filed April 20, 1888. Serial No. 271,337. Term of patent 14 years.

To all whom it may concern:

Be it known that we, WILLIAM WHARTON, Jr., and EDWARD SAMUEL, both citizens of the United States, and residents of Philadelphia, Pennsylvania, have invented a new and original Design for a Railroad Rail, of which the following is a specification.

Our design is fully shown in the accompanying drawing, which represents a transverse section of the rail.

The rail has a depending web, *a*, and the head of the rail projects laterally from one side of said web, and has a flat top, *b*, and a depending lug, *d*, at its outer edge. A finger, *f*, projects from the opposite side of the web, the course of this finger being first outward and then upward, so that between the finger and the head of the rail intervenes a deep groove, *g*.

We claim—

The within-described design for a railway rail having the outline illustrated, and consisting of the depending web *a*, having on one side a laterally-projecting head with flat top *b* and depending lug *d*, and on the other side an outwardly and upwardly extending finger, *f*, between which and the head of the rail intervenes a deep groove, *g*, all substantially as described and shown.

In testimony whereof we have signed our names to this specification in the presence of two subscribing witnesses.

WILLIAM WHARTON, JR.
EDWD. SAMUEL.
